UNITED STATES PATENT OFFICE.

JAMES C. JOHNSTON, OF GLENFIELD, ASSIGNOR OF ONE-HALF TO RICHARD B. DAVIS, OF PITTSBURG, PENNSYLVANIA.

MACHINE FOR MAKING CIGAR-BUNCHES.

SPECIFICATION forming part of Letters Patent No. 341,807, dated May 11, 1886.

Application filed August 13, 1885. Serial No. 174,303. (No model.)

To all whom it may concern:

Be it known that I, JAMES C. JOHNSTON, a citizen of the United States, residing at Glenfield, in the county of Allegheny and State of Pennsylvania, have invented new and useful Improvements in Machines for Making Cigar-Bunches, of which the following is a specification.

This invention relates to that class of machines for making cigars in which a recessed cylinder is provided with an apron passing over two small rollers for rolling the bunch and binder in a pocket of the apron between the small rollers. As heretofore constructed, the recessed cylinder has been arranged below the table of the machine, and after the bunch has been formed it is either discharged below the cylinder into a hopper or enters a recess in the cylinder, to be removed by hand.

The objects of my invention are to improve the construction of such machines; to provide a rotary block, in connection with an apron and rollers, whereby the bunch, after being formed, is automatically ejected upward to and upon the upper side of the cigar-board, which is used to support the tobacco prior to its being introduced into the pocket of the apron to be rolled into a bunch; to provide novel means whereby the binder for the bunch is automatically taken from the cigar-board and rolled around the bunch, after the tobacco to form the latter is introduced into the pocket of the apron, and to provide novel mechanism for rotating the block to effect the bunch-forming operation and for restoring the block to its position of rest to receive a supply of tobacco to form another bunch.

The objects of my invention I accomplish in the manner and by the means hereinafter described and claimed, reference being made to the accompanying drawings, in which—

Figure 1 is a front elevation of a cigar-machine constructed in accordance with my invention; Fig. 2, a vertical sectional view taken on the line $x-x$ of Fig. 1; Fig. 3, a detail perspective view, partly broken away, showing the bunch-forming devices; Fig. 4, a detail broken view showing the rotary block and apron portion to receive the tobacco; Fig. 5, a similar view showing the device in the act

of rolling the bunch; Fig. 6, a similar view showing the position of the block when about to effect the ejection of the rolled bunch to and upon the cigar-board; Fig. 7, a detail view showing one form of groove in the curved surface of the block to produce a particular shape of cigar, and Fig. 8 a similar view showing a modified form of groove to produce a different-shaped cigar.

In order to enable those skilled in the art to make and use my invention, I will now describe the same in detail, referring to the drawings, where the number 1 indicates a table supported by suitable legs or otherwise, and provided with an upright back piece, 2, and upright end pieces, 3. The table is furnished with a central opening, 4, around which is arranged a rectilinear frame composed of wooden front and back pieces and metallic end pieces, which support the horizontal cigar-board 4^a, to constitute a chamber above the table which contains the bunch-forming mechanism, which I will now set forth. In the metallic end pieces of the frame are mounted the journals on the end of the bunch-forming and apron-moving block 5, which, as shown, is semicircular in cross section, the apron 6 having its two ends suitably attached to the flat side of the block, and passing around two separated rollers, 7 and 8, the upper one, 7, of which is located directly beneath and in line with the inner or rear straight edge of the cigar-board 4^a. A third roller, 10, is arranged in front of the upper roller, 7, to guide the apron, and also act thereupon to preserve the pocket therein after the block has been turned to form a bunch. All of these rollers have the journals mounted in bearings in the metallic end pieces of the frame on the table. The block is cut away at the front side to form a longitudinal shoulder or ledge, 11, and a recess, 12, into which the slack of the apron can enter to form the pocket which receives the tobacco to be rolled into a bunch, and in the opposite side of the block is formed a longitudinal groove, 13, which constitutes the ejector for automatically discharging the formed bunch to and upon the cigar-board.

When the parts are in the position shown in Figs. 2 and 4, the tobacco is introduced by

the attendant into the pocket of the apron, and a binder is laid upon the cigar-board, so that the edge of such binder projects slightly beyond the rear straight edge of the board. The 5 block being now turned, its curved surface, acting upon the projecting edge of the binder, draws it into the pocket about the bunch, and the block being caused to make about two-thirds of a revolution, (more or less,) the bunch 10 and binder will be rolled into shape in the pocket of the apron between the upper and lower rollers, 7 and 8, such pocket and bunch never leaving the space between such rollers until the bunch is properly formed and ejected, as I will now explain.

After the block has been turned, as stated, to the limit of its movement in a forward direction, its longitudinal groove 13 is brought beneath and into coincidence with the pocket 20 and bunch, and the pocket enters such groove, as shown in Fig. 6. The block at this moment is suddenly retracted to its normal position, thereby automatically ejecting the rolled bunch and binder in an upward direction to and upon the cigar-board 4.

In order to actuate the block, a bar, 14, is attached midway, or nearly so, between its ends to one of the journals of the block, and to one end of this bar is secured a link, 15, 30 connected with a cord or chain, 16, which passes over a pulley, 17, mounted on the lower end of a pendent bracket, 18, which is rigidly connected with a bar secured to the back board, 2, of the table 1. The cord or chain connects with a treadle, 19, so that when the latter is depressed the bar 14 is brought to an approximately vertical position, and the block is rotated, as hereinbefore explained, to form the bunch. To the other end of the bar 14 is secured a link, 20, connected with a cord or chain, 21, which passes over a pulley, 22, on the bracket 18, and is furnished with a weight, 23, in such manner that when the bar 14 is in its vertical position and the treadle 19 is released the weight, acting through the cord or chain and link, will bring the bar 14 back to its normal position, thereby retracting the block to its position of rest, and automatically ejecting the formed bunch to and upon the 50 cigar-board, as before explained.

After the bunch and binder have been rolled into proper form, as described, they are to be introduced into a cigar-mold, to be pressed, and to effect this expeditiously as the bunches 55 are ejected upon the cigar-board, I provide an inclined standard, 24, in rear of the bunch-forming devices, for supporting a cigar-mold. This standard is attached at its lower end to the table 1 directly behind the back of the 60 frame, and from the upper end of the standard a vertical brace extends to the back piece, 2, of the table, where it is secured, for the purpose of bracing and sustaining the standard. A cigar-mold resting upon and supported by 65 the standard in an inclined position is in convenient position to receive the bunches after their ejection upon the cigar-board.

The curved surface of the block is continuously grooved longitudinally from the bunch-receiving recess 12 to the bunch-ejecting 70 groove 13, for the purpose of causing the apron to assume the shape of the grooved surface during the operation of rolling the bunch, thereby imparting to the latter the shape which the finished cigar is to possess. The 75 shape of such bunch-forming groove may be as shown in Fig. 7, or as in Fig. 8, or of any other shape suitable for the end to be attained.

It will be observed that the block and its journals are located entirely above the table 80 1, and that the block extends a considerable distance above the level of the cigar-board. This is very important, in that it not only permits the bunches to be rapidly and effectively produced, but also provides for the automatic 85 introduction of the binder from the cigar-board into the pocket of the apron, and also the automatic ejection of the rolled bunch to and upon the cigar-board when the block is retracted to its normal position for receiving 90 a supply of tobacco to form another bunch.

I would state that the front upper roller, 10, acting upon the apron during the movement of the block, preserves the necessary slack in the apron to create the pocket, and 95 such roller is very important to the practical and satisfactory working of the machine.

Having thus described my invention, what I claim is—

1. The combination of the cigar-board, the 100 rotary block, the apron, and the guide-rollers, said block having a curved surface extended above the cigar-board and provided with the bunch-receiving recess, and the groove for automatically ejecting the rolled bunch in an 105 upward direction to and upon the cigar-board, substantially as described.

2. The combination of the cigar-board, the apron, and the rotary block having a bunch-receiving recess, and a groove for receiving 110 the pocket after the completion of the bunch, to automatically eject the bunch in an upward direction to and upon the cigar-board, substantially as described.

3. The combination of the cigar-board, the 115 rotary block, the apron, the upper and lower guide-rollers around which the apron passes, and the upper front roller acting on the apron, said block extending above the level of the cigar-board and provided with a bunch-receiving recess, and a groove for automatically 120 ejecting the rolled bunch in an upward direction to and upon the cigar-board, substantially as described.

4. The combination of the apertured table, 125 the frame mounted on the table, the rotary block journaled in said frame, the cigar-board, the apron, and the guide-rollers, said block having its curved surface extending above the cigar-board and provided with a bunch-receiving recess, and a groove for automatically 130 ejecting the rolled bunch in an upward direction to and upon the cigar-board, substantially as described.

5. The combination of the cigar-board, the guide-rollers, the apron, and the rotary block having a bunch-receiving recess, and a groove for automatically ejecting the finished bunch 5 in an upward direction to and upon the cigar-board, with a bar secured to one of the journals of the block, a treadle connected with one end of said bar, and a weight connected with the other end of said bar, substantially 10 as described.
6. The combination of the table, the cigar-board, the guide-rollers, the apron, and the rotary block having a bunch-receiving recess, and a groove for automatically ejecting the 15 finished bunch in an upward direction to and upon the cigar-board, with a bar secured to one of the journals of the block, a pendent bracket having pulleys, a cord or chain con-
- nected with one end of said bar and with a treadle, and a cord or chain connected with 20 the other end of said bar and with a weight, substantially as described.
7. The combination of the cigar-board, the apron, the guide-rollers, and the rotary block having the bunch-receiving recess, the bunch-ejecting groove, and the bunch-forming groove formed continuously in its curved surface from said bunch-receiving recess to said bunch-ejecting groove, substantially as described. 25
- In testimony whereof I affix my signature in 30 presence of two witnesses.
